UNITED STATES PATENT OFFICE

DANIEL G. BUTTS, OF COVINGTON, LOUISIANA, ASSIGNOR TO THE FAULTLESS MANUFACTURING COMPANY, OF BALTIMORE, MARYLAND, A CORPORATION OF MARYLAND

GARMENT LOOP

Application filed August 21, 1930. Serial No. 476,899.

This invention relates to improvements in garment loops and particularly to loops of the type used in hosiery supports although it will be appreciated that loops of this type are capable of use in many other instances.

The primary object of my invention is to provide a garment loop or stud engaging clasp in which the edges of the material defining the throat leading to the stud receiving aperture are of a thickness equal to that of the blank of the material constituting the body portion or frame of the loop. In this connection it should be pointed out that in all known instances, the production of garment loops comprises the step of finishing and polishing the loops and the performance of these finishing and polishing operations has always resulted in a reduction of the thickness of the edges of the material defining the stud engaging and retaining throat portion. That is, the edges of the material defining these portions of the loop are reduced by the abrasion imposed upon them so that the edge portions are comparatively thin and, consequently, the constant use of the loop wears these thin edge portions away comparatively quickly and the resulting widening or enlargement of the throat soon renders the article useless. Specifically, this difficulty is overcome in the present instance by producing the loop in a form wherein the throat leading to the button or button shank receiving recess is not actually formed until the finishing and polishing steps have been performed. That is, the button or button shank recess is formed in the loop while the throat proper is still closed by a strip of material from which the loop is formed. The finishing and polishing processes are then carried out and after this has been done the strip across the throat is then removed so that it is impossible for the edges of the material constituting the throat to be rounded or beveled and thereby reduced in thickness.

With these and other objects in view, the invention consists in certain details of construction and combinations and arrangements of parts, all as will hereinafter be more fully described and the novel features thereof par-

ticularly pointed out in the appended claims.

In the accompanying drawings,

Figure 1 is a front elevation of a blank from which the preferred form of loop is to be produced;

Fig. 2 is a similar view showing the finished loop;

Fig. 3 is a sectional view taken on the line 3—3 of Fig. 2;

Fig. 4 is an end elevation of the loop with a button therein;

Fig. 5 is a front elevation of a blank from which a modified form of loop may be produced;

Fig. 6 is a similar view of a loop produced from the blank illustrated in Fig. 5, and

Fig. 7 is a similar view taken on the line 7—7 of Fig. 6.

As pointed out, the finished loop contemplated by the present invention might be said to be of uniform thickness having its edges buffed and rounded over so as not to cut or tear the cloth of the garment or the hands of the wearer. However, the edge portions of the material defining the throat or entrance in the button or button shank receiving recess are not reduced to a point where they will be quickly worn away through a constant use of the loop to such an extent

that the throat will be so enlarged as to not retain a button or button shank in the loop.

The production of such a loop may be accomplished from various materials but it is preferably formed from a stamped blank. In the

form of loop illustrated in Figs. 1 to 4 there is first produced a blank having a recess 10 and a cross bar 11 for attachment of the loop to the garment. In hose supporters the limb encircling portion of the supporter may be

run through the loop 10 or the bar 11 may be secured to the supporter by a suitable stitching. Likewise, in overalls the shoulder straps may be run through the recess 10. As

will be appreciated this portion of the loop for attachment to the hose supporter or other garment may take various forms and constitutes no portion of the present invention.

Spaced from the cross piece 11 are the transversely extending portions 12 and projecting from those portions is what will be

termed the body or frame proper. This body or frame consists of the side portions 13 merging into the end portion 14. The shape or contour of this frame may be altered as desired but extending inwardly therefrom are projections 15 converging toward one another to form the throat 16 through which the button or button shank must enter the recess 17. In producing the present loop the blank is stamped from the material in the form shown in Fig. 1 where it will be noted that the projections 15 for defining the throat 16 are connected by a cross strip 18. After the blank has been produced in this form the finishing and polishing operations are then imposed thereon and after this has been accomplished said connecting strip 18 is then removed to produce the completed loop shown in Fig. 2. By carrying out the finishing and polishing steps before removing the cross connecting strip 18 from the throat defining portions of the loop, the edge portions of the projections 15 defining the throat 16 are not reduced in thickness as shown in full lines in Fig. 3. To more clearly illustrate the present invention there is shown in dotted lines, at 19, in Fig. 3 (more or less diagrammatically, of course) the results of the finishing and polishing operations on the throat defining portions of a loop where the loop is formed by a method which does not provide means for preventing a reduction in thickness of these throat defining portions. It will be appreciated that where the throat defining portions of the loop are reduced in thickness, as indicated in the dotted lines at 19, this more or less rounded or knife like edge of the material will be rather quickly worn away by the constant use of the loop and as a result the throat is widened or enlarged thereby permitting a button or button shank to more readily escape from within the receiving recess 17.

In garment loops or clasps of this character, the shank of a stud secured to one member of the garment is passed through a restricted throat and stud shank receiving aperture in the clasp which is secured to another member of the garment. Such restricted throat portions are generally slightly closer to each other than the diameter of the stud shank and the stud shank is really "snapped" through the throat portion into the receiving aperture and may be disengaged only by pressing or "snapping" it outwardly through the restricted throat.

In the form of loop shown in Figs. 1 to 4 the location of the projections 15 and their disposition with respect to the size and end of the frame is such that the spreading strains placed upon the throat defining portions 15 as the stud is drawn therethrough do not effect permanent widening of the throat. In other words, the sides of the frame may be flexed either outwardly or inwardly but the

position of the projections with respect to one another or, in other words, the width of the throat 16 will not be affected.

In Figs. 5 to 7 there is illustrated a loop 1 conforming in outline to loops heretofore produced but, like the form of my invention shown in Figs. 1 to 4, the loop illustrated in these figures differs from previous loops in that the thickness of the material defining the throat 16 has not been affected by the polishing or finishing operations performed in the production of the loop. In this embodiment there is the cross member 11 and strip recess 10 with the cross piece 12 merging into the sides 13 of the loop. In this form, as in the form illustrated in Figs. 1 to 4, the throat 16 is slightly less in width than the diameter of the stud shank so that the sides 13 of the frame are temporarily minutely distorted outwardly as the stud shank is passed through the throat, in a sort of snapping engagement into the recess 17. In both illustrated forms of garment clasps, it is this tendency of the stud shank to expand the throat constituting portions of the clasp which results in wear and enlargement of the throat, and which wear is materially resisted by the broad, square throat edges of clasps embodying my invention. As shown in Fig. 5, those portions of the sides 13 that are to form the throat 16 in the finished loop are connected by the cross strip 18 in the blank from which the finished loop is to be produced. The finished loop is illustrated in Fig. 6, showing the throat merging into the button or stud shank receiving recess 17 and, in Fig. 7, there is shown more or less diagrammatically the difference between the loop formed from the blank wherein the cross strip 18 is not removed until after the finishing and polishing operations are performed as compared with the loop produced by a method wherein the recess 17 and throat portion 16 are formed before the finishing and polishing operations. As will be seen from Fig. 7, the throat defining portions of the material are the same thickness throughout the sides 13 of the loop where the present method is pursued in the production of the loop but, as indicated in dotted lines at 19, these throat defining portions are beveled or rounded, or otherwise reduced in previous forms of loop produced by a method wherein the cross strip 18 is not present during the finishing and polishing steps.

What I claim is:

1. A fastening device for connecting two members comprising a stud having an attaching portion, a straight shank, and an enlarged head, and a stamped clasp member for engagement with said stud having an attaching portion, a pair of apertures, and a slot or throat connecting said apertures, one of said apertures being larger and the other being smaller than the head of said stud, said

- clasp having its peripheral edge and its internal edges bounding said apertures buffed and rounded over, said slot or throat having a width slightly less than the diameter of
5 said stud shank and the edges of said clasp bounding said slot or throat being square with the adjacent clasp portions and having a complete bearing upon the straight shank of the stud as it is drawn therethrough.
- 10 2. A fastening device for connecting two members comprising a stud having an attaching portion, a straight shank, and an enlarged head, and a stamped clasp member for engagement with said stud having an attaching portion, a stud receiving aperture and a slot or throat through which said stud is drawn into said aperture, said clasp having its peripheral edge and its internal edge bounding said aperture buffed and rounded
15 over, said slot or throat having a width slightly less than the diameter of said stud shank and the edges of said clasp bounding said slot or throat being square with the adjacent clasp portions and having a complete bearing upon
20 the straight shank of the stud as it is drawn therethrough.
